UNITED STATES PATENT OFFICE

164,406

SUGAR BOWL

R. Guy Cowan, Fayetteville, N. Y., assignor to
Onondaga Pottery Company, Syracuse, N. Y., a
corporation of New York

Application July 13, 1950, Serial No. 11,132

Term of patent 14 years

(Cl. D44—21)

To all whom it may concern:

Be it known that I, R. Guy Cowan, a citizen of the United States, residing at Fayetteville, State of New York, have invented a new, original, and ornamental Design for Sugar Bowl, of which the following is a specification, reference being had to the accompanying drawing, forming a part hereof.

Figure 1 is a top plan view of a sugar bowl embodying my new design.

Figure 2 is a partial sectional view taken on line 2—2, Figure 1.

Figure 3 is a side elevational view.

Figure 4 is a partial sectional view taken on line 4—4, Figure 3.

I claim:

The ornamental design for a sugar bowl, as shown.

R. GUY COWAN.
